UNITED STATES PATENT OFFICE.

JOSEPH S. JONES, OF BROOKLYN, AND SAMUEL N. MEAD, JR., OF BALDWIN, NEW YORK,
ASSIGNORS TO CHAS. CORY & SON, INC., OF NEW YORK, N. Y., A CORPORATION OF
NEW YORK.

TELEPHONE TRANSMITTER.

Application filed November 24, 1925. Serial No. 71,032.

Our invention relates to improvements in telephone transmitters, and more particularly to the group of parts constituting variable contact mechanism of the "carbon" type.

The general object is to provide carbon contact mechanism in which the chamber is especially shaped and adapted to maintain the comminuted carbon or graphite which 10 constitutes the variable conducting medium in a uniform normal arrangement and state of compactness, in co-operation with a button especially conformed to co-operate with the chamber in properly maintaining the 15 graphite particles in such uniform state of compactness and arrangement, regardless of the position of the transmitter in which the contact mechanism is employed.

Another object is to improve details of 20 construction of such contact devices in various ways, sufficiently explained hereafter.

The accompanying drawing shows one exemplifying embodiment of the invention. After considering this example, skilled persons will understand that many variations 25 may be made without departing from the principles of the invention, and we contemplate the employment of any structures that are properly within the scope of the appended claims.

Fig. 1 is a view in side elevation of a telephone transmitter with the casing and other parts broken away or sectioned to show the contact mechanism, which is represented 30 mainly in longitudinal section.

Fig. 2 is a front elevation of the contact mechanism with some parts broken away.

Fig. 3 is an enlarged, part-sectional detail 35 of the button and related parts.

In Fig. 1, 1 is the casing of any known or 40 suitable telephone transmitter having any suitable diaphragm (not shown) properly supported within the front portion 2. Within the casing is any suitable framework 45 3 having an aperture at 4 to receive a metal contact base or support 5 which constitutes one of the terminals, as indicated by a conductor 6 soldered or otherwise suitably secured thereto. A cup 7 of insulating material, such for example as hard rubber or 50 a synthetic-resin composition, is secured to the terminal or base 5 by a screw 8 having a thin, flat, wide circular head 9 lying against the inner bottom of the cup. A thin 55 circular carbon disk 10 is located in close

contact with the screw head 9 and is secured in any known or suitable way. Specifically, in the present instance, the disk is held with a press fit in a counterbore 11, and the walls of the cup forming the periphery of the counterbore are provided with small lugs 12 engaging notches in the disk to aid in its retention. Outward from the counterbore and the outer surface of the carbon disk, the cup is shaped to provide a chamber 13 of generally shallow cylindrical contour, but with a substantial curve or fillet 14 at the bottom of the cylindrical wall, so that the general form of the chamber, as well defined by a longitudinal section-plane, as shown in Fig. 1, is that of a shallow cup. The outer face of the chamber is closed by a flexible disk 20 of mica or other suitable insulating material, clamped against the outer face of the cup wall by a flanged ring nut or bezel 21. The mica disk is clamped to the button structure, as best shown in Fig. 3, including the button proper, 25, which has an inward, shallow conical face or head 26. The outward portion of the head consists of a shallow cylindrical member 27 having an external screw thread to receive a locking flange 28 provided with spanner sockets 29. The locking flange 30 clamps the mica disk 20 against the outward face of the button head surrounding the threaded member 27. A small screw-threaded stem 30 extends outward from the center of the button portion 27 and engages in a suitable threaded bore of a rod or connector 31, Fig. 1, which is in turn connected to the diaphragm to vibrate the button structures.

The chamber defined by the interior formation of the cup, as above described, the 95 flexible disk 20 and the inner conical face 26 of the button, is substantially filled with comminuted carbon 35.

The button or its outer locking flange 28 constitutes the other terminal of the contact 100 mechanism and a conductor 40 is secured thereto by soldering or otherwise.

The carbon chamber as will now be understood, is not only in the form of a shallow cup, but its outward portion, defined 105 by the inner face of the button, is in the form of a shallow conical concavity. This chamber formation in cooperation with the button serves to retain a relatively small mass of carbon particles in substantially 110

uniform arrangement and compactness between the button and the carbon disk, and so to maintain to a high degree the uniform action of the comminuted carbon in varying 5 the current flow in response to diaphragm movements, in whatever position the transmitter may be placed. This is especially important and useful when the transmitter is more or less portable and may be tilted at 10 almost any angle, as for instance when it is incorporated in telephone equipment designed for attachment to the body of an operator.

In addition to the form of the chamber 15 serving to properly maintain the comminuted carbon mass in uniform arrangement or compactness, the shallow conical form of the button provides an advantageous and effective movable contact for accurately conveying to the compressible carbon mass the 20 varying pressure effects derived from diaphragm movements.

We claim:

1. Telephone transmitter contact mechanism comprising a cup, a shallow conical button therein, and a flexible disk connecting the button and the cup, the parts named forming a shallow and flat-bottomed cupped chamber with a concave shallow conical outer face, the chamber being approximately 25 filled with comminuted carbon.

2. Telephone transmitter contact mechanism comprising a cup of insulating material having a central counterbore, a thin 30 carbon disk secured in the counterbore, the disk and adjacent cup walls defining the inner contour of a shallow cup-formed chamber having a flat bottom and with curved contours adjacent the periphery of the disk, 35 and a shallow conical button defining the principal part of the outward portion of the chamber.

3. Telephone transmitter contact mechanism comprising a cup of insulating material having a central counterbore, a thin 40 carbon disk secured in the counterbore, the

disk and adjacent cup walls defining the inner contour of a shallow cup-formed chamber having a flat bottom and with curved contours adjacent the periphery of the disk, 45 a shallow conical button defining the principal part of the outward portion of the chamber, and a flexible disk securing the button to the cup.

4. Telephone transmitter contact mechanism comprising a cup of insulating material having a central counterbore, a thin carbon disk secured in the counterbore, the disk and adjacent cup walls defining the inner contour of a shallow cup-formed chamber having a flat bottom and with curved contours adjacent the periphery of the disk, 50 a shallow conical button defining the principal part of the outward portion of the chamber, and a flexible disk securing the button to the cup, the chamber so defined being approximately filled with comminuted carbon which is maintained in a uniform arrangement and normal compression by the stated chamber formation, irrespective 55 of tilting of a transmitter in which the mechanism is incorporated.

5. Transmitter contact mechanism comprising a cup of insulating material, a contact-base therefor, a screw passing through the cup bottom engaging a threaded bore in the base, the screw having a thin flat head located in the bottom of a counterbore at the inside of the cup bottom, a thin carbon disk secured in the counterbore 60 against the screw head, the wall of the cup outward from the disk defining a shallow cup having a flat bottom and with substantial curvature adjacent the periphery of the carbon disk, and a button flexibly secured 65 to the cup and forming the outward portion of a carbon chamber.

Signed at New York city, in the county of New York and State of New York this 18th day of Novbr. A. D. 1925.
